UNITED STATES PATENT OFFICE.

ALGOT A. WICKLAND, OF CHICAGO, AND FREDERICK K. VIAL, OF LAGRANGE, ILLINOIS,
ASSIGNORS TO GRIFFIN WHEEL COMPANY, OF CHICAGO, ILLINOIS, A CORPORATION
OF MASSACHUSETTS.

CHARGING MACHINE.

Application filed November 26, 1919. Serial No. 340,819.

To all whom it may concern:

Be it known that we, ALGOT A. WICKLAND, of Chicago, Illinois, and FREDERICK K. VIAL, of LaGrange, Illinois, citizens of the United States, residing as above stated, in the county of Cook and State of Illinois, have invented a new and useful Improvement in Charging Machines, of which the following is a specification.

10 This invention relates to charging devices for foundry cupolas, furnaces and the like and has for its object broadly the provision of new and improved charging apparatus and adapted to place the charge accurately 15 in a desired portion of the cupola, furnace or other receiving apparatus, or to distribute the charge evenly therein.

An important object of the invention is the provision of a charging apparatus of 20 simple, efficient character for feeding a number of series of cupolas, furnaces or other receiving apparatus through the provision of a small amount of equipment.

Another important object of the invention 25 is the provision of a charging apparatus for feeding one or more cupolas or furnaces and requiring a minimum of manual labor and a minimum number of operators and attendants.

30 Another important object of the invention is the provision of a charging apparatus which will receive a wheeled truck carrying the material forming the charge and pour the material from the truck into any of a 35 number of cupolas and from certain aspects of the invention into a single cupola.

Another object of the invention is the provision of an apparatus accomplishing these 40 and other valuable results, parts of which will be so constructed and arranged as to render unlikely the necessity of frequent repair, replacement, and readjustment and which apparatus will be power actuated in its several movements and functions.

45 Numerous other objects and advantages of the invention will be apparent as the invention is better understood from the following description, which when considered in connection with the accompanying drawings 50 discloses a preferred embodiment thereof.

On the drawings,

Fig. 1, is a diagrammatic plan view of a foundry cupola organization of which the

charging apparatus embodying our invention is selected for the purposes of illustration, forms a part.

55 Fig. 2, is a diagrammatic vertical view through the same.

Fig. 3, is an end view of the charging apparatus or conveyor embodying our present invention.

60 Fig. 4, is a side view of the same; and

Fig. 5, is a front to back vertical section.

For the purposes of illustrating the invention we have shown in Fig. 1 a schematic 65 layout of a possible cupola organization in a foundry and on this figure reference characters 11 indicate the cupolas. In front of these cupolas are provided tracks 12 extending in front of the series of cupolas and on

70 which moves a charging apparatus or conveyor 13. Delivery tracks 14 for wheeled trucks are provided, as are also storage tracks 15 in any suitable number and in any suitable arrangement. A crane 10 is provided to deposit the trucks on the tracks 14.

Viewing Fig. 2 it will be noted that the 75 cupolas are in the present instance of relatively large dimension and provided with the charging openings 16 adjacent the charging 80 tracks 12. The charging tracks as has been stated extend past the cupolas and the charging apparatus is adapted to receive and carry the trucks or containers containing the material to be deposited in the cupolas and to dump such material from said trucks or

85 containers by tilting them to a pouring position as indicated in dotted lines in Fig. 2. As will be presently more fully understood, the charging apparatus is adapted to move 90 the trucks when tilted and pouring out the contents backwardly and forwardly in the cupola and from side to side, and in combinations of these movements as occasion may require or render desirable.

95 The charging apparatus comprises a main conveyor frame of substantial I-beam construction and comprising side I-beams 21 and end I-beams 22 suitably connected together and braced and supported on shafts 23 at each side, which shafts carry flanged truck or car wheels 24 upon the two rails 25 constituting the charging track or tracks, bearings 26 being provided and supporting the framework by U-straps or bolts 27. The 100 frame also comprises upwardly extending

side wings 28 of heavy material and secured upon the tops of the end I-beams. The side wings are provided with cross shafts 29 extending between them and also stub shafts 30, said shafts 29 and 30 carrying rollers 31 between which is mounted a frame laterally movable of the charging truck and toward and from the cupola. This frame comprises I-beams 32 engaged between the 10 rollers at each side and connected at their ends by I-beams 33, additional I-beams 34 arranged parallel to and connected to the I-beams 32 are also provided, the connections being by castings 35 disposed with- 15 in the I-beams 32. These last mentioned I-beams support a pivotally mounted truck support on which the truck 36 may be disposed. This support comprises two side members 37 mounted near the ends adjacent 20 the cupolas on the pivot shaft 38 and at the other ends connected by a cross member 39, which in normal receiving position rests upon the I-beam 34. The track frame is thus pivotally mounted on the shaft 38 and carries at its top Z-bars 39 which form the rails. These Z-bars are turned up at their ends at 41 to provide curves into which the forward wheels of the trucks fit when the 25 tilting frame is tilted about its pivot shaft 38 preventing the truck running off the rails. It is intended that this pivotal movement may be as much as 90 degrees and to prevent the truck falling away from the track, angle bars 42 are secured in the upwardly extending 30 flanges 43 of the Z-bars and these angle irons are adapted to be engaged by cooperating hooked castings 44 carried on the journal boxes 45 of the trucks. The rails formed by the Z-bars and the tilting frame are 35 relatively short and extend merely throughout a distance amply sufficient to accommodate the truck. The Z-bar rails register with rail sections 46 carried on the I-beams 34 on suitable ties 47 and these rails 46 40 extend into position to receive the truck from the feeding or supply rails when the apparatus is arranged in receiving position.

A hooked bracket 83 may be secured to the far side of the rail 25, which is at the 50 greater distance from the cupola or the like, by any suitable means, such as by bolts 84, and a bracket 85 may be secured to the side wings 28 of the frame by any suitable means, such as by bolts 86 or the like, which is 55 adapted to engage the hooked bracket 83 to insure against a tipping of the charging apparatus 13 when the trucks 36 are heavily loaded.

Power mechanism is provided for driving 60 the entire charging mechanism along the charging tracks, for moving the horizontally movable frame toward and from the cupolas and for tilting the truck and returning it to normal position, which power mechanisms 65 will now be described. Considering first the

mechanism for advancing the charging apparatus along the charging track, a motor 48 is mounted upon an extension 49 of the main frame of the apparatus. The shaft 51 of this motor carries a gear 52 meshing with a gear 53 on a shaft 54 having bearings in upwardly extending brackets 55 on such extension. The shaft 54 is provided with a pinion 56 in mesh with a gear 57 fast on one of the car wheel or truck wheel shafts of 70 the apparatus. The motor through the gearing described rotates the shaft and propels the apparatus in either direction as may be desired. 75

The mechanism for moving the horizontally movable frame comprises a motor 61 mounted at the side of the apparatus. This motor through a worm and gear drive 62 drives a shaft 63 carrying a pinion 64 meshing with a gear 65 upon a shaft 66 carrying pinions 68, said shaft having bearings at 67 in the side wings. The pinions 68 mesh with racks 69 on the under faces of the I-beams 34. 80 85

The mechanism for tilting and lowering the tiltable support comprises a motor 71 supported by a strap 72 from the I-beams 34 which motor actuates a worm and wheel drive 73, the worm and wheel drive in turn actuating a cross shaft 74 having bearings at 75 from the I-beams 34 and carrying two 90 pinions 76. These pinions 76 mesh with and drive rack segments 77 integral with and extending down beneath the side members of the tiltable support. 95

The control for the several actuating and driving mechanisms is conveniently located above a platform 81 supported from the extension 49 in the main frame, one of said controls 82 being shown for the purposes of illustration. 100

In the operation of the apparatus the truck is run across the track sections 46 and on to the tiltable support. The charging apparatus is then brought adjacent the cupola in which the charge is to be deposited and the horizontally movable frame moved forward into charging position. The tiltable support is then tilted to cause the contents to pour from the truck and during this pouring operation the horizontally movable frame may be moved back and forth, i. e. inwardly and outwardly, of the cupola to accurately deposit the material or spread it as may be required. Sidewise motion may also be given the car during the pouring operation by moving the entire charging apparatus along the charging track. Combinations of these two movements may be employed and the pouring accomplished in a circular fashion into the cupola. 110 115 120 125

It will be manifest that the apparatus is of simple character and can easily be controlled by a single attendant during the charging operation.

It is thought that the invention and many 130

of its attendant advantages will be apparent without further description and it will be obvious that various changes may be made in the form, construction and arrangement 5 of its parts without departing from the spirit and scope of the invention or sacrificing all of its material advantages, the form hereinbefore described being merely a preferred embodiment thereof.

10 We claim:

1. In an apparatus adapted to charge cupolas, furnaces, or the like, the combination of a container for the charging material, a wheeled conveyer mounted beneath and supporting said container, and means including said conveyor for moving said container forwardly and backwardly and in sidewise direction for distributing the contents thereof while said contents are being discharged 15 within the cupola, furnace, or the like.

2. In an apparatus adapted to charge cupolas, furnaces, or the like, the combination of a container for the charging material, a wheeled conveyer mounted beneath and supporting said container, and means including said conveyor for effecting universal movement of said container for distributing the contents thereof while said contents are being discharged within the cupola, furnace, 20 or the like.

3. In an apparatus adapted to charge cupolas, furnaces, or the like, the combination of a container for the charging material, a wheeled conveyer mounted beneath and supporting said container, and means including said conveyor for moving said container forwardly and backwardly for distributing the contents thereof while said contents are being discharged within the 35 cupola, furnace, or the like.

4. In an apparatus for charging cupolas, furnaces and the like, the combination of a wheeled container for bringing material to the cupola and mechanical means for bodily 45 tilting said wheeled container while within the cupola to dump the contents thereof directly upon the hearth of said cupola.

5. In an apparatus for charging cupolas, furnaces, and the like, the combination of a 50 container for delivering material to the cupola, tracks for said container, means for tilting the tracks and container to permit the container to pour its contents into said cupola, and means for moving said conveyor bodily forwardly and backwardly while in tilted position.

6. In an apparatus for charging cupolas, furnaces, and the like, the combination of a 55 wheeled container for delivering material to the cupola, tracks for said container, means for mechanically tilting the tracks and container to permit the container to pour its contents into said cupola, said track being provided with obstructions to prevent the container running off the ends thereof when

in tilted position, and means for moving said conveyor bodily forwardly and backwardly while in tilted position.

7. In an apparatus for charging cupolas, furnaces, and the like, the combination of 70 a wheeled container for delivering material to the cupola, tracks for said container, means for tilting the tracks and container to permit the container to pour its contents into said cupola, said tracks being bent 75 up at their ends to prevent the container running off the ends thereof when in tilted position, and means for bodily reciprocating said container while in tilted position.

8. In an apparatus for charging cupolas, 80 furnaces and the like, the combination of a container for delivering material to the cupola, tracks for said container, means for tilting the tracks and container to permit the container to pour its contents into 85 said cupola, means movable with the tracks and engaging the container for preventing it falling away in the tilting action, and means for bodily reciprocating said container while in tilted position. 90

9. In an apparatus for charging cupolas, furnaces and the like, the combination of a container for delivering material to charging position, tracks for said container, means for tilting the tracks and container 95 to permit the container to pour its contents into the cupola, furnace, or the like to be charged and movable means for supporting said track and moving it in tilted position backwardly and forwardly to distribute the charge over a substantial area. 100

10. In an apparatus for charging cupolas, furnaces and the like, the combination of a container for delivering material to charging position, tracks for said container, means for tilting the tracks and container to permit the container to pour its contents into the cupola, furnace, or the like to be charged and movable means for supporting said track and moving it in tilted position 105 sidewise and forwardly and backwardly to distribute the charge over a substantial area. 110

11. In an apparatus for charging cupolas, furnaces and the like, the combination of a container for delivering material to the charging position, tracks for said container, means for tilting the tracks and container to permit the container to pour its contents 115 into the cupola, furnace, or the like to be charged and movable means for supporting said track and moving it in tilted position sidewise, backwardly and forwardly to distribute the charge over a substantial area. 120

12. The combination of a series of cupolas or the like, a track extending lengthwise thereof, a wheeled frame on said track, a track extending transversely of said wheeled frame and a wheeled carrier movable onto said last mentioned track whereby to per- 125 130

- mit the container carrying track to be positioned adjacent any of said cupolas or the like and moved into operative relation therewith.
5. 13. The combination of a series of cupolas or the like, a track extending lengthwise thereof, a wheeled frame on said track, a longitudinally movable track extending transversely of said wheeled frame and a 10 wheeled carrier movable onto said last mentioned track whereby to permit the container carrying track to be positioned adjacent any of said cupolas or the like and moved into operative relation therewith.
15. 14. The combination of a series of cupolas or furnaces, a track for carrying a wheeled
- 20 container, and means for moving said track into position before any of said cupolas or the like and then inwardly into operative relation with said cupola or the like to permit discharge of the contents of said container.
- 25 15. In an apparatus for charging cupolas, furnaces and the like, the combination of a wheeled charge carrying truck, a transfer device for arranging the truck adjacent a cupola, and means for distributing charges carried by said truck over the hearth of said cupola as an incident to the unloading thereof.

ALGOT A. WICKLAND.
F. K. VIAL.
